Fig. 3.

Fig. 4.

Fig. 1.

Fig. 2.

FIG. 1 is a front view of a toilet tank showing my new design;

FIG. 2 is a left side elevational view thereof;

FIG. 3 is a right side elevational view thereof; and
FIG. 4 is a top plan view thereof.

This is a division of design application Ser. No. D. 20,960, filed Jan. 16, 1970, now abandoned.

The broken line representation of a flush handle in the figures is for purposes of illustration only.

The characteristic feature of my design resides in the graining striations extending from an upper corner of a substantially rectangular tank and radiate downward across the front of the tank towards the diagonal opposite corner.

I claim:

The ornamental design for a toilet tank, as shown and described.
